UNITED STATES PATENT OFFICE.

GILBERT L. CROWELL, JR., OF ARLINGTON, NEW JERSEY, ASSIGNOR TO
DOMINICK & HIAFF, OF NEW YORK, N. Y.

DESIGN FOR A BACK FOR BRUSHES, &c.

SPECIFICATION forming part of Design No. 24,918, dated November 26, 1895.

Application filed October 5, 1895. Serial No. 564,809. Term of patent 14 years.

To all whom it may concern:

Be it known that I, GILBERT L. CROWELL, Jr., a citizen of the United States, residing at Arlington, in the county of Hudson and State 5 of New Jersey, have invented and produced a new and original Design for the Backs of Brushes, Mirrors, and other Articles, of which the following is a description, reference being had to the drawings accompanying and forming 10 a part of the same.

Figure 1 of the drawings shows in plan the back of a brush or mirror bearing my design. Fig. 2 shows an enlarged section on plane zz of Fig. 1.

15 The general outline of the back is of the oval form shown.

A is a vine border running around the edge of the back and down around the spatulate handle of the back. The space on the back 20 included by this border is divided off into a series of plain panels B, C, D, E, and F, which panels are without surface decoration. These panels are separated from each other by the raised ribs G, of form substantially as

shown in Fig. 2. The panels and ribs converge to a common center piece, such as the disk H, surrounded by the vine border I.

The striking features of this design to the eye (and which cannot be shown by drawing) are the plain and polished panels arranged 30 practically on one curving plane (see Fig. 2) and yet having the appearance of being much more inclined to each other than they in fact are, which effect is largely due to these panels being separated by the radial V-shaped 35 ribs G. In this connection it is immaterial what is the design at the border, the essential feature of the design being the radial arrangement or plain or panel-like surfaces separated by the raised ribs, as shown.

40 What is claimed as new is—

The design for the back of a brush, mirror or similar article, substantially as shown and described.

GILBERT L. CROWELL, JR.
